[57] CLAIM

The ornamental design for a combined air pillow and utility bag, as shown and described.

DESCRIPTION

FIG. 1 is a perspective view of a combined air pillow and utility bag, showing my new design;

FIG. 2 is a front-elevational view thereof;

FIG. 3 is a rear-elevational view thereof; and

FIG. 4 is a cross-sectional view taken substantially along line 4—4 of FIG. 1 with the inflatable inner bag shown in full.

FIG. 1

FIG. 2

FIG. 3

FIG. 4
